United States Patent Office

Des. 189,184
Patented Nov. 8, 1960

189,184

CAN OPENER

Ivar Jepson, Oak Park, and Burton Kelly, Bellwood, Ill.,
assignors to Sunbeam Corporation, Chicago, Ill., a cor-
poration of Illinois

Filed Aug. 28, 1959, Ser. No. 57,368

Term of patent 14 years

(Cl. D22—2)

FIG. 6.

Fig. 1 is a front perspective view of a can opener embodying our new design;

Fig. 2 is a top plan view thereof;

Fig. 3 is a right side elevational view thereof;

Fig. 4 is a left side elevational view thereof;

Fig. 5 is a sectional view thereof taken substantially along line 5—5 of Fig. 1; and

Fig. 6 is a rear elevational view thereof.

The essential features of the design reside in the portions shown in solid lines on the drawing.

We claim:

The ornamental design for a can opener, as shown and described.
